SAFETY CONTROL FOR GASEOUS FUEL
BURNERS

Harold W. Rice, Los Angeles, and George B. Solovieff, South Gate, Calif., assignors to Robertshaw-Fulton Controls Company, a corporation of Delaware

Application April 26, 1945, Serial No. 590,470

16 Claims. (Cl. 158—117.1)

1

This invention relates to safety control apparatus for fuel burners and, more particularly, to combined resetting and indicating devices for thermomagnetic safety controls.

One object of the invention is to reset the thermomagnetic safety device and indicate the control position by a common operation.

Another object of the invention is to facilitate the resetting operation by utilizing the simple rotation of a dial for this purpose.

Another object of the invention is to indicate clearly the operational sequence for resetting the control.

Another object of the invention is to automatically retain the setting dial in an operated position if the control is properly set in operation.

Another object of the invention is to automatically return the setting dial to unoperated position if the control is not functioning.

Another object of the invention is to prevent flow of fuel to the main burner during the resetting operation while permitting such flow to a pilot burner.

Other objects and advantages will become apparent from the following description taken in connection with the accompanying drawings, wherein—

Fig. 1 is a cross section to a thermomagnetic safety control embodying the invention;

Fig. 2 is a partial cross section of the control shown in Fig. 1 but showing the operating parts in another position;

Fig. 3 is a view similar to Fig. 2 but showing the parts in still another operating position;

Figs. 4, 5 and 6 are plan views showing the indicating device in various positions;

Fig. 7 is a plan view of a detail;

Fig. 8 is a side elevation of the detail shown in Fig. 7; and

Fig. 9 is a perspective view of the detail shown in Figs. 7 and 8.

Referring more particularly to the drawings, the safety control comprises a casing 10 provided with an inlet 12 and an outlet 14 suitably threaded for connection to a gaseous fuel supply pipe 15 which supplies fuel to a main burner (not shown). The casing 10 is provided with an interior partition 16 between the inlet 12 and outlet 14 having an annular valve seat 18. For a purpose which will be apparent hereinafter, the interior wall of the annular valve seat member 18 is provided with a circumferential recess 20 positioned intermediate the ends of the member and defining the

2

margin of a conical opening 22 which extends from one end of the valve seat member 18.

The opposite end of the valve seat member 18 is adapted to be engaged by a disc valve member 24 which is biased to its seat by a coil spring 26. A closure plate 28 surmounts the end of the casing 10 beyond the valve member 24 and provides an abutment for the opposite end of the spring 26. A valve stem 30 projects from the valve member 24 through the closure plate 28 and suitable packing 32 may be provided to seal the closure plate against leakage past the valve stem 30.

The projecting end of the valve stem 30 carries an armature 34 cooperable with the pole faces of a horseshoe magnet 36 and being spaced therefrom when the valve member 24 is engaged with the valve seat 18. The magnet 36 is secured to a hood 38 which is carried by the closure plate 28 and suitably insulated therefrom. The usual coil or winding 40 is provided for the magnet 36 and has one end grounded on the hood 38 and the opposite end connected to a terminal conductor 42 suitably insulated from the hood 38 and projecting to the exterior thereof.

Abutting against the underside of the valve member 24 is a spring plate 44 in the form of a narrow strip of yieldable material having a plurality of depending fingers 46 engageable with the conical opening 22 in the valve seat member 18. The spring plate 44 is engaged on the underside by one end 48 of a connecting stem 50. While the valve member 24 is not secured to the connecting stem 50 in order to permit floating movement relative to the valve seat member 18, it is apparent that a threaded or other connection could be provided at this point. The opposite end of the connecting stem 50 threadedly engages with a reset stem 52 which extends through a housing 54 carried in the bottom of the casing 10. The reset stem 52 is provided with a head 56 which may conveniently be formed by undercutting a recess 55 in the adjacent end of the stem 52 but which could be equally well formed by making the head 56 of larger diameter than the stem 52 as will be apparent. In addition, the reset stem 52 is provided with a collar 58 intermediate the ends thereof and adapted to be engaged by a slideable element in the form of a thimble 60 mounted in the housing 54.

The thimble 60 is retained in the housing 54 by the provision of an annular flange 62 thereon which engages with the wall of a recess 64 formed in the housing 54 for this purpose. As previously indicated, the thimble 60 is adapted for slideable

movement in the housing 54 and will initially move relative to the reset stem 52 which extends therethrough. However, subsequently to this initial movement of the thimble 60, the upper face thereof engages with the collar 58 on the reset stem 52. Upon further slidable movement of the thimble 60 relative to the housing 54 a joint movement of the thimble 60 and the reset stem 52 will occur relative to the housing 54.

As such movement of the reset stem 52 will cause corresponding movement of the connecting stem 50 and the valve member 24, it will be apparent that fuel will flow from the inlet 12 past the valve seat member 18 and between the fingers 46 to the outlet 14. It is assumed that the control device will be provided with a pilot burner, as indicated at 66, and means are provided for supplying such burner with fuel when the valve member 24 is off its seat while at the same time preventing flow of fuel from the outlet 14. Thus, as will now be explained, during the operation of resetting the armature 34 against the pole faces of the magnet 36 only the pilot burner 66 is supplied with fuel.

To this end, a duct 68 is provided in the valve seat member 18, preferably between the recess 20 therein and the seat for the valve member 24, and this duct 68 communicates with a passage 70 extending through the casing 10 into communication with the pilot burner 66 which is supported thereby. The flow of fuel to the outlet 14 is prevented by a flow interrupting device comprising a closure disc 72 slidably mounted on the reset stem 52 beyond the collar 58. The disc 72 is of sufficient area to extend beyond the periphery of the valve seat member 18 from which it is normally biased by a coil spring 74 operable between the margin of the disc 72 and the valve seat member 18.

The closure disc 72 has a yieldable diaphragm 76 secured at its peripheral edge thereto and clamped between the connecting stem 50 and the reset stem 52 at its inner portion. A pair of sealing rings 78 and 80 are secured respectively to the peripheral portions of the diaphragm 76 and the closure disc 72 for alternative engagement with the valve seat member 18 and the housing 54, respectively. A coil spring 82 extends between the underside of the closure disc 72 and the upper side of the flange 62 formed on the thimble 60 and serves to bias these elements apart.

The pilot burner 66 is located in proximity to a thermocouple 84 having one lead 86 electrically connected to the terminal conductor 42 and the other lead 88 grounded on the hood 38. The thermocouple 84 is thus adapted to be heated by a flame from the pilot burner 66 but is incapable of generating sufficient current to attract the armature 34. However, the thermocouple 84 will generate sufficient current to retain the armature 34 against the pole faces of the magnet 36 after the armature has been moved into engagement with the pole faces by operation of the reciprocal means including the thimble 60 and reset stem 52 as will now be described.

Secured to the housing 54 is a support plate 90 which may be circular and have its axis offset from the axis of the housing 54. A dial plate 92 is carried by the support plate 90 in axial alignment therewith but longitudinally spaced therefrom. The dial plate 92 is perforated to permit the head 56 of the reset stem 52 to extend therethrough in different longitudinal positions depending upon the position of the reset stem 52. Rotatable means in the form of a handle 94 and

stem 96 therefor are mounted axially on the dial plate 92 with a projecting end 98 of the stem 96 extending through the support plate 90 to provide an additional bearing for the rotatable means. A spacing collar 100 is formed on the stem 96 and is located between the support plate 90 and the dial plate 92. A pointer 102 is fastened to the underside of the handle 94 adjacent the dial plate 92 across which it is movable by rotation of the handle 94. The pointer 102 is thus adapted to register with indicia 104 on the outer surface of the dial plate 92 comprising the words "Off," "On" and "Light pilot" arranged in spaced sequence as shown in Fig. 4. A torsion spring 106 is mounted between the handle 94 and the dial plate 92 and serves to bias the handle 94 in a counter-clockwise direction.

A cam disc, shown in detail in Figs. 7, 8 and 9 and designated generally by the reference numeral 108, is fastened to the stem 96 between the collar 100 and the inner face of the dial plate 92 for rotation relative to the latter when the handle 94 is rotated. The cam plate 108 may be formed from a single sheet of material and has an offset segment portion 110 thereon from the plane of the plate. Preferably, the offset portion 110 has a sloping face 112, a level face 114 forming the high point of the cam and an end face 116 extending substantially normal to the plane of the cam disc 108. The offset portion 110 may conveniently be formed by slitting the cam disc 108 on the arcuate inner periphery 118 of the segment from which it is formed. It will be apparent, however, that the offset portion 110 could be formed from a separate piece of material welded or otherwise secured to the walls of a segmental opening formed in the cam disc 108.

An arcuate slot 120 is formed in the cam disc 108 adjacent its periphery and extending through substantially 180 degrees of the circumference thereof. The arcuate slot 120 is located partly in the sloping face 112 and in the level face 114 of the offset portion 110 where it takes the form of an enlargement 122 terminating adjacent the end face 116. At the opposite end of the enlargement 122 which is beyond the offset portion 110 is a shoulder 124 formed at the junction of the enlargement 122 with the narrower part of slot 120. The enlargement 122 thus terminates substantially midway of the ends of the slot 120 and beyond the adjacent end of the offset portion 110.

The enlargement 122 is adapted to receive the head 56 of the reset stem 52 but the head is unable to enter the narrower portion of the slot 120 beyond the shoulder 124. The reduced portion 55 of the reset stem 52 is, however, capable of entering the narrower portion of the slot 120 beyond the shoulder 124 for a purpose which will be hereinafter apparent. The cam disc 108 is mounted on the stem 96 in such position relative to the dial plate 92 that when the operating parts of the control are in the position shown in Fig. 1 then the reset stem 52 is located at the end of the narrow portion of slot 120 remote from shoulder 124 which is "Light pilot" position as shown in Fig. 4. The pointer 102 then indicates the "Off" position being located opposite the end of the enlargement 122 remote from the shoulder 124.

In the operation of the device it is assumed that the valve member 24 is engaged with the valve seat 18, the armature 34 is consequently spaced from the pole faces of the magnet 36 and the reciprocal means including the reset stem 52 and thimble 60 are in extended position shown in Fig.

1. The pointer 102 is then in the position shown in Fig. 4 indicating that the fuel flow is turned "Off." Rotation of the handle 94 in a clockwise direction will engage the sloping face 112 of the cam disc 108 with the projecting end of the thimble 60. Further movement in this direction will cause the thimble 60 to ride up the sloping face 112 and engage the level face 114 of the cam disc with consequent slidable movement of the thimble 60 relative to the housing 54 and the reset stem 52. During this rotation of the cam disc 108, the slot 120 therein has moved relatively to the reset stem 52 so that the stem is now within the enlargement 122.

As soon as the thimble 60 is moved by the cam disc 108 inwardly of the housing 54 the force applied by the spring 82 is transmitted to the closure plate 72 against the bias of the spring 74. As the spring 82 is stronger than the spring 74, the closure disc 72 is moved toward the valve seat member 18 causing the sealing ring 78 to be moved into sealing engagement therewith. The thimble 60 now engages with the shoulder 58 on the reset stem 52 causing a joint movement of the thimble and reset stem inwardly of the housing 54. The inward movement of the reset stem 52 is communicated by the connecting stem 50 and the spring plate 44 to the valve member 24 which is lifted off its seat against the bias of the spring 26 and the armature 34 is placed in engagement with the pole faces of the magnet 36. The depending fingers 46 of the spring plate 44 ride up the conical inner surface wall of the opening 22 of the valve seat member 18 and snap into the recess 20 formed therein. Thus, the connecting stem 50 is retained in the raised position with the valve member 24 open and the armature 34 in engaged position. The reset stem 52 is now located with respect to the cam disc 108 at the end of the enlargement 122 remote from the shoulder 124 and the head 56 is in the plane of the cam disc 108 received within the enlargement 122. The pointer 102 is indicating the "Light pilot" position as shown in Fig. 5 and the operating parts are in the positions shown in Fig. 2.

The valve member 24 being now disengaged from the valve seat 18, fuel is permitted to flow from the inlet 12 through the duct 68 and passage 70 to the pilot burner 66 where it can be ignited. It will be apparent that as the flow interrupting device is operative with the sealing ring 78 engaged with the valve seat member 18 no fuel can flow from the outlet 14 to the main burner. The flame from the pilot burner 66 heats the thermocouple 84 and generates sufficient current for the coil 40 to energize the magnet 36 and retain the armature 34 in engagement with the pole faces thereof.

This resetting operation occupies but a few seconds and then the handle 94 can be released. The torsion spring 106 will return the handle and pointer 102 in a counter-clockwise direction causing a corresponding movement of the cam disc 108. However, as the head 56 of the reset stem 52 is now held in the plane of the slot 120 by the position of the reset stem 52, the cam disc 108 can rotate only until the shoulder 124 engages the head 56. When such engagement occurs the pointer 102 is indicating the "On" position which is intermediate the "Off" and "Light pilot" positions on the dial plate 92 as shown in Fig. 6.

It is apparent, therefore, that while the rotatable means of this device comprising the handle

94 and cam disc 108 can move in a forward direction throughout 180 degrees of movement, the rotation of the rotatable means in a reverse direction is substantially one-half the rotation in forward direction provided that the armature is reset. Should the armature 34 for some reason fail to be retained in engagement with the pole faces of the magnet 36 then the reduced portion of the reset stem 52 would be in the plane of the arcuate slot 120 and the shoulder 124 would be ineffective to limit the rotation of the cam disc 108 in reverse direction.

As during the reverse rotation of the cam disc 108 the level face 114 is moved away from the thimble 60 and the sloping face 112 is also subsequently moved away, the thimble 60 is moved by the spring 82 to its initial position as shown in Fig. 3. The release of the pressure of the spring 82 on the closure plate 72 will permit the spring 74 to bias the closure plate 72 to disengage the sealing ring 78 from the valve seat member 18. The other sealing ring 80 is now moved into engagement with the housing 54 serving to prevent leakage of fuel past the thimble 60 or the reset stem 52 as might occur now that the valve 24 is off its seat. Thus, fuel from the inlet 12 to both the pilot burner 66 and the outlet 14 to the main burner now occurs as long as the current generated by the thermocouple 84 continues.

In the event that the flame from the pilot burner 56 is extinguished and the thermocouple 84 ceases to generate sufficient current to retain the armature 34 in engagement with the pole faces of the magnet 36, then the flow of fuel to the main burner through the outlet 14 and to the pilot burner 66 is automatically shut off. In this operation, the valve member 24 is moved into engagement with the valve seat member 18 by the bias of the spring 26 causing disengagement of the depending fingers 46 of the spring plate 44 from the recess 20. The connecting stem 50 and reset stem 52 are thus moved to initial position with the head 56 beyond the plane of the cam disc 108. The arcuate slot 120 in the cam disc 108 now moves relative to the reset stem 52 due to the reduced portion 55 thereon being in the plane of the cam disc 108. The torsion spring 106 which serves to rotate the rotatable means including handle 94 in a counter-clockwise direction will cause the pointer 102 carried thereby to register with the "Off" position on the dial plate 92 giving visual warning to the operator that the device is inoperative.

The safety control of this invention eliminates confusion and danger in igniting the pilot of an appliance with which the control is used. A single dial is used for resetting and indicating purposes. The operator is protected from the flow of fuel to the main burner during the operation of lighting the pilot burner. Moreover, visual indication is afforded of the position of the valve member in the "Off" and "On" positions thereof. In addition, visual indication is afforded of the precise position in which the handle should be placed while the pilot burner is being lighted.

It will be apparent that many changes can be made in the arrangement and combination of parts and in the details of construction herein disclosed within the scope of the appended claims without departing from the spirit of the invention.

We claim:

1. In a control device, the combination of controlling means movable between flow permitting

and preventing positions, an electromagnetic device having an armature operative for retaining said controlling means in said flow permitting position, means for resetting said armature in operative position relative to said electromagnetic device including reciprocable means operatively associated with said armature and controlling means, rotatable means movable to an operative position for operating said reciprocable means, means for biasing said rotatable means to an inoperative position, interengaging means on said reciprocable means and said rotatable means effective in said operative position for preventing return movement of said rotatable means under said bias to said inoperative position when said armature is reset, and indicating means cooperative with said interengaging means for defining positions of said controlling means corresponding to the operative or inoperative position of said rotatable means.

2. A control device comprising a casing having inlet and outlet passages and a valve seat, valve means cooperable with said seat for controlling the flow between said passages, said valve means having a plurality of operative positions relative to said seat including full and minimum flow positions, an electromagnetic device having an armature operative for retaining said valve means in said full flow position, means for resetting said armature in operative position relative to said electromagnetic device including reciprocable means operatively associated with said armature and valve means, said reciprocable means being biased to one position and being movable therefrom to cause said valve means to assume said minimum flow position, and means carried by said casing and engageable with said reciprocable means for limiting return movement thereof under said bias when said armature is reset and causing said valve means to assume said full flow position.

3. A control device comprising a casing having inlet and outlet passages and a valve seat, valve means cooperable with said seat for controlling the flow between said passages, said valve means having a plurality of operative positions including full and minimum flow positions, an electromagnetic device having an armature operative for retaining said valve means in said full flow position, means for resetting said armature in operative position relative to said electromagnetic device including reciprocable means operatively associated with said armature and said valve means, rotatable means biased to one position and being movable against said bias to another position for operating said reciprocable means to cause said valve means to assume said minimum flow position, interengaging means on said reciprocable means and said rotatable means effective in said other position for preventing return movement of said rotatable means under said bias to said one position when said armature is reset and limiting said return movement to an intermediate position to cause said valve means to assume said full flow position, and indicating means cooperative with said interengaging means for defining said full and minimum flow positions in the intermediate and other positions respectively of said rotatable means.

4. A safety control for fuel burners comprising means movable between positions for controlling the flow of fuel, an electromagnetic device having an armature operable for retentively positioning said controlling means when said device is energized, means for resetting said arm-

ture relative to said electromagnetic device including a reciprocable stem for operating said armature and controlling means, means carried by said stem for limited slidable movement thereon, rotatable means offset from said stem, a cam element carried by said rotatable means for movement into and out of engagement with said slidable means for effecting said limited slidable movement followed by operation of said stem, and means operable by said slidable means during said limited slidable movement thereof for interrupting the flow of fuel to the burner during the resetting operation.

5. A safety control for fuel burners comprising means movable between positions for controlling the flow of fuel, an electromagnetic device having an armature operable for retentively positioning said controlling means when said device is energized, means for resetting said armature relative to said electromagnetic device including reciprocable means operatively associated with said armature and controlling means, rotatable means offset from said reciprocable means, an element carried by said rotatable means for movement into and out of engagement with said reciprocable means for operating the same, means carried by said reciprocable means for interrupting the flow of fuel during the resetting operation, and means operatively associated with said flow interrupting means for preventing leakage of fuel past said reciprocable means upon completion of the resetting operation.

6. A safety control for fuel burners comprising a casing having a valve seat therein, a valve member engageable with one side of said valve seat, an electromagnetic device having an armature spaced from said valve member and movable between attracted and released positions, a stem for operating said armature and valve member and projecting beyond said casing, means carried by the projecting end of said stem for limited slidable movement thereon in a first direction toward said valve seat, said slidable means forming a closure for said casing and being engageable therewith for limiting said slidable movement in a second direction away from said valve seat, means carried by said casing and operable for moving said slidable means in said first direction, means responsive to the last said movement of the slidable means for engaging in flow interrupting relation with the opposite side of said valve seat from said valve member, said stem being thereafter moved by further operation of said moving means to unseat said valve member and reset said armature in attracted position, means carried by said stem and engageable with said valve seat for retaining said stem in said moved position, yieldable means operable between said slidable means and said flow interrupting means for returning said slidable means in said second direction upon cessation of operation of said moving means, and means associated with said flow interrupting means and engageable with said casing upon said return movement of said slidable means for sealing said casing closure.

7. A safety control for fuel burners comprising a casing having a valve seat therein, a valve member engageable with one side of said valve seat, an electromagnetic device having an armature spaced from said valve member and movable between attracted and released positions, a stem for operating said armature and valve member and projecting beyond said valve member exteriorly of said casing, a thimble slidably mounted on the projecting end of said stem and forming

a closure for said casing, said stem having a shoulder thereon engageable by said thimble for limiting slidable movement thereof in a first direction toward said valve seat, said thimble having a shoulder thereon engageable with said casing for limiting slidable movement of said thimble in a second direction away from said valve seat, manually operable means carried by said casing for moving said thimble in said first direction, means responsive to the last said movement of the thimble for engaging in flow interrupting relation with the opposite side of said valve seat from said valve member, said stem shoulder being thereafter engageable by said thimble for moving said stem to unseat said valve member and reset said armature in attracted position, means carried by said stem and engageable with said valve seat for retaining said stem in said moved position, and yieldable means operable between said thimble and said flow interrupting means for returning said thimble in said second direction upon cessation of operation of said manually operable means.

8. A safety control for fuel burners comprising a casing having a valve seat therein, a valve member engageable with one side of said valve seat and biased to closed position, an electromagnetic device having an armature spaced from said valve member and biased to a released position, a stem associated with said armature and valve member and operable for moving said valve member to open position and said armature to attracted position, a thimble carried by said stem and projecting beyond said casing, said stem having a shoulder thereon engageable by said thimble for limiting slidable movement thereof toward said valve seat, flow interrupting means carried by said stem and engageable with the opposite side of said valve seat from said valve member, means for biasing said flow interrupting means away from said valve seat, manually operable means carried by said casing for moving said thimble toward said valve seat, and yieldable means between said thimble and said flow interrupting means for transmitting movement of one to the other, said biasing means being overcome by said thimble movement for engaging said flow interrupting means with said valve seat, said stem shoulder being thereafter engageable by said thimble for moving said stem to open said valve while said flow interrupting means remains engaged with said valve seat.

9. In a control apparatus, control means reciprocal between positions of operation, means for biasing said control means to one of said positions, means for actuating said control means against its bias to another said position including a control member offset from said control means and adapted for manual rotation in a forward direction, spring means for returning said member in a reverse direction when manual operation is terminated, means carried by said control member and having an arcuate slot therein, and a stem projecting from said control means into said slot for limiting the rotation of said control member in both said directions.

10. In a control apparatus, control means reciprocal between positions of operation, means for biasing said control means to one of said positions, means for retaining said control means in another said position but being incapable of actuating it to said other position, means for actuating said control means against its bias to said other position including a control member

offset from said control means and adapted for manual rotation in a forward direction, spring means for returning said member in a reverse direction when manual operation is terminated, means carried by said control member and having an arcuate slot therein defining three control positions one of which is intermediate the other two control positions, and a stem projecting from said control means into said slot for limiting the rotation of said control member in said forward direction to establish one of said control positions and in said reverse direction to establish the other two control positions, said intermediate position being established only if said control means is retained.

11. The combination with a controlling means movable between positions and biased to one of said positions, means for retaining said controlling means in another position against its bias but incapable of actuating it from said one position, of means for actuating said controlling means including reciprocal means associated with said controlling means, rotatable means offset from said reciprocal means, a cam disc movable by said rotatable means into operative engagement with said reciprocal means for actuating said reciprocal means, said disc having an arcuate slot therein into which said reciprocal means is adapted to project, and means operatively associated with said disc and rotatable means for defining control positions for the latter corresponding to the positions of said controlling means, said reciprocal means and slot cooperating to retain said rotatable means in one control position when said controlling means is retained in said other position thereof.

12. The combination with a controlling means movable between positions and biased to one of said positions, means for retaining said controlling means in another position against its bias but incapable of actuating it from said one position, of means for actuating said controlling means including reciprocal means associated with said controlling means, rotatable means offset from said reciprocal means, a cam disc movable by said rotatable means into operative engagement with said reciprocal means for actuating said reciprocal means, said disc having an arcuate slot therein provided with an enlargement at one end terminating at the median portion thereof, said reciprocal means being adapted to project within said slot and having a head engageable with said enlargement but incapable of entering beyond said median portion, a dial plate through which said reciprocal means and rotatable means are adapted to project and having indicia defining control positions for the latter corresponding to the positions of said controlling means, and a pointer carried by said rotatable means and movable relative to said indicia, said reciprocal means and slot cooperating to limit the rotation of said rotatable means in both directions and said enlargement and head cooperating to retain said rotatable means in one control position when said controlling means is retained in said other position thereof.

13. A safety control for fuel burners comprising means movable between positions for controlling the flow of fuel, an electromagnetic device having an armature operable for retentively positioning said controlling means when said device is energized, means for resetting said armature in engagement with said electromagnetic

device including a reciprocable stem for operating said armature and controlling means, means carried by said stem for limited slidable movement thereon, rotatable means offset from said stem and adapted for forward and reverse rotation, an element carried by said rotatable means for movement into and out of engagement with said slidable means for effecting said slidable movement followed by operation of said stem during said forward rotation, and means operatively associated with said element and stem for limiting the rotation of said rotatable means in one direction to less than the rotation in the other direction when said armature is reset.

14. A safety control for fuel burners comprising means movable between positions for controlling the flow of fuel, an electromagnetic device having an armature operable for retentively positioning said controlling means when said device is energized, means for resetting said armature in engagement with said electromagnet device including a reciprocable stem for operating said armature and controlling means, means carried by said stem for limited slidable movement thereon, rotatable means offset from said stem and adapted for forward and reverse rotation, an element carried by said rotatable means for movement into and out of engagement with said slidable means for effecting said limited slidable movement followed by operation of said stem during said forward rotation, an arcuate slotted portion on said element having an enlargement terminating intermediate the ends thereof, and a head on said stem movable into operative engagement with said enlargement by said stem operation for limiting the rotation of said rotatable means in reverse direction to substantially one-half the rotation in forward direction when said armature is reset.

15. A safety control for fuel burners having main and pilot burners comprising means movable between positions for controlling the flow of fuel to the burners and being biased to one of said positions, an electromagnetic device having an armature operable for retentively positioning said controlling means when said device is energized, thermoelectric means exposed to a flame from the pilot burner for energizing said electromagnetic device, means for resetting said armature in engagement with said electromagnetic device and actuating said controlling means against its bias to another position including a reciprocable stem for operating said armature and controlling means, means carried by said stem for limited slidable movement thereon, means responsive to said limited slidable movement for interrupting the flow of fuel to the main burner during the resetting operation, rotatable means offset from said stem and adapted for rotation in forward and reverse direction, a cam disc carried by said rotatable means and movable into engagement with said slidable means for effecting said limited slidable movement followed by operation of said stem during rotation in forward direction to complete the resetting operation, said disc having an arcuate

slot therein into which said stem projects and defining three control positions, one said control position being established when said armature is disengaged, the second said position being established upon completion of the resetting operation, and the third said control position being established only if said armature remains engaged when said rotatable means is returned in reverse direction from the second control position.

16. A safety control for fuel burners having main and pilot burners comprising a casing having a valve seat therein provided with a duct communicating with the pilot burner, a valve member engageable with one side of said seat and adapted to control flow of fuel to both the main and pilot burners, means for biasing said valve member to closed position, an electromagnetic device having an armature spaced from said valve member and movable between attracted and released positions, a stem for operating said armature and valve member and projecting beyond said casing, thermoelectric means exposed to a flame at the pilot burner for energizing said electromagnetic device, means carried by the projecting end of the stem for limited slidable movement thereon, means operatively engageable by said slidable means for movement into engagement with the opposite side of said valve seat to interrupt the flow therethrough, manually rotatable means offset from said stem and adapted for rotation in forward and reverse direction, spring means for returning said rotatable means in reverse direction when manual operation in forward direction is terminated, a cam disc carried by said rotatable means and movable into engagement with said slidable means for effecting said limited slidable movement followed by operation of said stem during rotation in forward direction to complete the resetting operation, said disc having an arcuate slot therein into which said stem projects and defining the "Off," "Light pilot" and "On" positions, said "Off" position being established when said armature is disengaged, said "Light pilot" position being established upon completion of the resetting operation, and said "On" position being established only if said armature remains engaged when said rotatable means is returned in reverse direction from said "Light pilot" position.

HAROLD W. RICE.
